UNITED STATES PATENT OFFICE.

RANSOM W. DAVENPORT, OF DETROIT, MICHIGAN, ASSIGNOR TO DETROIT STOVE WORKS, OF DETROIT, MICHIGAN, A CORPORATION OF MICHIGAN.

ELECTRICAL FITTING.

1,145,057.

Specification of Letters Patent.

Patented July 6, 1915.

Application filed November 25, 1912. Serial No. 733,519.

To all whom it may concern:

Be it known that I, RANSOM W. DAVENPORT, a citizen of the United States of America, residing at Detroit, in the county 5 of Wayne and State of Michigan, have invented certain new and useful Improvements in Electrical Fittings, of which the following is a specification, reference being had therein to the accompanying drawings.

10 The invention relates to electrical fittings and is more particularly designed for use in connection with electrical heaters and other electrical instruments.

It is the primary object of the invention 15 to provide in a single compact fitting a controlling switch and a socket connector for the detachable coupling of the heater or other instrument; further, to combine in said fitting a fuse-holder; and further, to 20 so design and construct the fitting that it may be easily mounted upon the stove or other device to which it is applied, and compactly arranged and associated with similar fittings for controlling other circuits.

With these objects in view the invention 25 consists in the construction as hereinafter set forth.

In the drawings: Figure 1 is a sectional 30 end elevation of the fitting; Fig. 2 is a perspective view of the insulator body or block detached; Fig. 3 is a front elevation of a stove, showing a series of fittings applied thereto and the manner of mounting 35 the same thereon; Fig. 4 is a front elevation of Fig. 2; Fig. 5 is a perspective view, showing the rear side of the fitting. Fig. 6 is a diagram showing the arrangement of circuits.

40 In the construction of electric stoves, it is usual to provide a plurality of electrical heating units for different purposes, such as baking oven, broiler, surface heater, etc., and which are separately controlled. Each 45 of these units should be controlled by an independent fuse and a switch, and for permitting removal or exchange of the unit there should be provided a detachable connector. With my improved construction a 50 single fitting is adapted to form these several functions, the construction being as follows: A is a body or block of insulating material, such for instance as porcelain; B is a control switch mounted upon the block 55 A; and C are fuse-holders also formed in

the block. To permit of employing a standard construction of switch, the block A is provided with a seat D for the usual round switch base, and beneath this seat is a recess E for receiving the connectors F leading to the fuse-holders or sockets C.

For convenience in mounting, the block A is preferably of rectangular form and is provided on opposite parallel edges with grooves G, which are adapted to slidably 65 engage rods or bars H on the mounting. As shown in Fig. 3, a series of fittings are mounted adjacent to each other at the front of the electric stove, the front rail I of which forms the upper guide bar, while a lower bar H is supported by brackets J at opposite ends thereof, depending from and secured to said rail I. The service conductors K extend longitudinally of the entire series and are arranged in grooves L in the 70 rear side and adjacent to the opposite edges of the block. Connection to these conductors is made through clamping contacts M arranged in recesses N in the block and secured by a screw O, forming one of the contacts for the fuse socket C. The same screw clamps the annular contact P for said socket to the connector F leading to the switch B.

75 Connection to the heating units or other electrical instrument to be controlled is formed by a detachable plug-connector, which engages socket contacts in the block A through entrance apertures in the rear face thereof. As shown, Q is the plug-connector, which may be merely an insulated 80 wire having a bared end. R are apertures in the rear face of the block A, which are in alinement with the several contacts S of the switch, and with the apertures therefor in the switch base B'. The socket contact is 85 preferably formed by a recessed rod T having a reduced end 'T' which engages the clamp U of the switch contact U'. The opposite end of said rod, which is recessed, extends into the aperture R. Two of these 90 contacts are clamped to the connectors F by suitable nuts F' engaging the threaded exterior of the rods. The recess portion is also preferably split to form a yieldable, resilient socket. Thus by merely inserting the 95 end of the connectors Q into the aperture R it will be electrically connected with the rod T and through the latter with the switch contacts.

100 In Fig. 6 is illustrated a specific applica- 110

tion of the fitting to a heater circuit, in which the switch contacts S and S' are connected by the connectors F and fuses C respectively to the leads or service conductors 5 K. The heating resistor V is provided with three conductors V, V² and V³, leading from the opposite ends of the resistor and from an intermediate point, and the ends of these conductors may be respectively engaged 10 with the contact members S² S and S³. This will permit of developing either low or high heat by manipulation of the switch, so as to bridge alternatively between the contacts S S' and S² S³, while in intermediate position 15 the circuit will be open.

When it is desired to develop high heat, the contacting members S' S² are bridged, causing the current to pass through the conductor V² and the resistor V, the current 20 then passing on through the carrier F and the fuse block adjacent thereto. When low heat is used the contacts S' S³ are bridged, the current passing through one half of the resistor and leading out through the conductor F. The contacts S S' are bridged 25 when the heating resistor is not in use, the current then passing through the conductor F, without entering the resistor.

As shown in Fig. 3, a series of the fittings 30 may be arranged adjacent to each other and connected to the same leads or service conductors, while all of the circuits controlled by said fittings may be conveniently and detachably connected therewith. All of the 35 live contacts are completely concealed and protected by insulation, and at the same time the fittings are readily mounted or detached by merely clamping or unclamping the contacts M and removing the block from the 40 supporting rails H and I.

If desired a plate of insulating material 45 may be arranged to cover the backs of the fittings, in which case naked service wires may be employed.

What I claim as my invention is:

1. An electrical fitting comprising an insulator block, there being grooves arranged in the block whereby the same may be en-

gaged by a mounting, said block having connected sockets in one of its faces, a switch 50 in one of said sockets, a fuse arranged in an adjacent socket, an electrical connector between said switch and fuse, and a plug receiving socket contact connected to a switch contact opening through the opposite face 55 of the block.

2. An electrical fitting comprising an insulator block, recessed in one face to form connected sockets, a switch in one of said sockets, a fuse in another of said sockets, an 60 electrical connector between said switch and fuse, and a plug-receiving socket contact connected to a switch contact, opening through the opposite face of said block.

3. An electrical fitting comprising a rectangular block having grooves in opposite edges thereof for engagement with the mounting, the front face of said block being recessed and the rear face longitudinally grooved, a switch and fuse socket in said recess, a connector for attachment to a service conductor in the groove on the rear face of said block, and a plug-receiving socket contact connected to a switch contact and extending into an aperture in the rear face of 75 said block.

4. An electrical fitting comprising a rectangular block grooved upon opposite edges for engagement with a mounting, recessed on its front face, longitudinally grooved 80 upon its rear face for the reception of service conductors, and apertured through the rear face, a switch mounted in the recess in said front face, a plug-receiving contact in the aperture in said rear face and connected 85 to one of the switch contacts, a fuse-holder also in said front recess, and a connector between said fuse socket and the conductor in said rear groove.

In testimony whereof I affix my signature 90 in presence of two witnesses.

RANSOM W. DAVENPORT.
